CONNECTION FOR FILAMENT AND LEAD WIRES

Wells J. Meeker and Lucas Renfle, Warren, Ohio,
assignors to General Electric Company, a corporation of New York

Application July 1, 1938, Serial No. 217,000

3 Claims. (Cl. 176—38)

Our invention relates to incandescent lamps, radio tubes and other electrical devices enclosed within a sealed bulb or container, and more particularly to the attachment of the filament or other resistance element of said devices to the inner leads thereof.

Usually the filament or the resistance element of such electric devices is connected to the inner leads by means of hooks formed by bending back the end portions of said leads which are closed on the ends of said filament or resistance. When the ends of the filament are coiled, the hooks are closed only enough to hold the filament securely, in order to avoid crushing and probable injury thereto. To close the hooks the correct amount has, however, proven very difficult and the said hooks are sometimes not closed tightly enough to hold the filament. This condition occurs most often when the filament and leads are brought together manually and clamped.

An object of our invention is to provide an improved joint between a filament and a lead-in wire. Another object is to provide a lead-in wire with a filament-engaging hook so formed as to hold the filament securely and prevent injury thereto even though the hook is closed more or less tightly than normally allowable. Another object is to provide a lead wire with a filament-engaging hook having its inner surface so formed as to prevent slipping of the end of a coiled filament therefrom without the necessity of gripping the filament so tightly as to injure it. Other features and advantages of our invention will be apparent from the following detailed description of species thereof and from the accompanying drawing.

In the drawing Fig. 1 is a perspective view of an incandescent lamp embodying a filament joint construction comprising our invention; Fig. 2 is an enlarged perspective view showing one end of a filament joined to a lead wire in accordance with our invention; Fig. 3 is a sectional view on a still larger scale of the hooked end of the lead wire with the end of the filament secured therein; and Fig. 4 is an elevation on an enlarged scale of a portion of a lead wire having an end of modified form, said end being shown prior to its formation into a hook.

The incandescent lamp shown in Fig. 1 comprises a bulb 10 in which is sealed a filament 11 of a refractory metal such as tungsten. The filament 11 is connected to the inner ends of the leading-in wires 12 and 13 which extend through the conventional tipless stem 14 to the metal shell 15 and end eyelet 16 respectively, of the

standard base 17. Additional support is provided for the mid-portion of the filament 11 by the wire 18 which is looped thereabout and has one end embedded in the button on the end of the glass arbor 19 extending from the stem 14.

In this particular instance the filament 11 is of coiled-coil form, as shown in Fig. 2, and has its singly coiled end portions 20 clamped in hooks 21 formed on the ends of the lead-in wires 12 and 13. Each hook 21, as shown in the enlarged view of lead-in 12 shown in Fig. 2, is formed from a flattened end portion of said lead-in wire which is bent back on itself and which, in this instance, is provided on its inner surface with longitudinal ridges 22 which engage the turns of the end portion 20 of the filament. The ridges 22 are not necessarily spaced the same distance apart as the coils of the end portion 20 of the filament but tend to hold said filament securely, since they lie approximately parallel to said coils and a goodly portion of said ridges projects between said coils. The hooks are not closed tightly since the coils of the filament ends 20 would be crushed and very likely injured. However, the said coils are usually flattened to a certain extent as shown in Fig. 3. The ridges 22 in the lead-in wires 12 and 13, which in this instance are made of nickel, usually are also distorted somewhat by the filament coils so that a more effective electrical connection is made. Both the greater gripping effect as well as the resilience provided by the ridges contribute to the superiority of this type of hook since they insure that a more loosely as well as a more tightly clamped hook will hold the filament satisfactorily.

Obviously other shapes and forms of protuberances or roughening than the ridges 22 may be provided on the inner surfaces of the hooks 21. The said surfaces of the hooks may, for instance, be knurled to provide diamond-shaped protuberances such as shown on the flattened end portion 23 of the lead-in wire 24 in Fig. 4. The said end portion 23 is shown prior to its formation into a hook.

What we claim as new and desire to secure by Letters Patent of the United States is:

1. In an electrical device comprising a sealed container, the combination of a closely coiled filament in said container and an inner lead connected thereto, said inner lead having a hook on an end thereof clamped around a portion of said filament, the inner filament-engaging surface of said hook being roughened to securely grip the turns of said filament.
2. In an electrical device comprising a sealed

5 container, the combination of a closely coiled filament in said container and an inner lead connected thereto, said inner lead having a hook on an end thereof clamped around a portion of said filament, the inner filament-engaging surface of said hook having protuberances thereon at least some of which extend into the spaces between the turns of said filament to securely grip it.

10 3. In an electrical device comprising a sealed

5 container, the combination of a closely coiled filament in said container and an inner lead connected thereto, said inner lead having a hook on an end thereof clamped around a portion of said filament, the inner filament-engaging surface of said hook being provided with longitudinally extending ridges for securely gripping the turns of said filament.
